(57) **CLAIM**

We claim the ornamental design for a single dose liquid medication dispenser, as shown and described.

DESCRIPTION

FIG. 1 is a perspective view of a single dose liquid medication dispenser showing our new design;

FIG. 2 is a front elevational view thereof, the rear elevational view being identical thereto;

FIG. 3 is a bottom plan view thereof;

FIG. 4 is a side elevational view thereof, the elevational view of the opposing side being identical thereto;

FIG. 5 is a top plan view thereof; and,

FIG. 6 is a reduced perspective view showing the single dose liquid medication dispenser in use; the broken lines depict environmental structure for illustrative purposes only and form no part of the claimed design.
